UNITED STATES PATENT OFFICE.

JAMES WALTER ADAMS AND OTTO HENRY EGGE, OF SPRECKELS, CALIFORNIA.

PROCESS AND APPARATUS FOR MIXING DRY LIME WITH LIQUIDS.

1,269,994.

Specification of Letters Patent. Patented June 18, 1918.

Application filed February 24, 1917. Serial No. 150,880.

To all whom it may concern:

Be it known that we, JAMES WALTER ADAMS and OTTO HENRY EGGE, citizens of the United States, residing at Spreckels, in the county of Monterey and State of California, have invented new and useful Improvements in Processes and Apparatus for Mixing Dry Lime with Liquids, of which the following is a specification.

This invention relates in general to processes and apparatus for applying dry powdered lime to sugar solutions and pertains particularly to an improvement in processes and apparatus for distributing lime evenly to the surface of the solutions to be treated.

The invention includes the process and means for maintaining the lime particles in a dry condition until they are actually projected into the sugar solution.

One object of the invention is to distribute the lime evenly over a specified area of the surface of a body of sugar solution and to accomplish this and provide the desired resultant mixture and avoid the common fault caused by the formation of thick lime deposits on the walls of the treatment chamber and cooler.

By the present invention we overcome the difficulty experienced in the use of other distributors in which the fine lime settles on the foam in the cooler and treatment chambers which forms a crust of lime eventually carried into the circulating well of the apparatus used. The crust is commonly found not in a finely divided state but in lumps and as such does not re-act with the sugar but hydrates or slacks when mixed with a solution thus producing heat which is undesirable and rendering the lime inactive and useless.

Further the present invention renders it difficult for the lime to collect on the sides of the cooler wall or on the sides of the walls of the treatment chamber. Heretofore this collection of lime has fallen off in chunks and dropping into the solution has raised the temperature of the solution as above noted or lodged in lumps in the circulating tube, plugging these tubes and often making it necessary to cut the cooler and entire apparatus out of service so that the structure may be opened up and cleaned. The present invention also makes it possible to apply the

lime more quickly because of the high efficiency of the same.

The present invention renders possible the desirable equal distribution of powdered lime over a specified area of the cooler solution in such a manner that a uniform quantity of lime is constantly coming in contact with a uniform and proportionate amount of sugar solution. The present invention renders this function in the most efficient manner by conveying the lime to the solution in the shortest possible time after it leaves the feeding device and enters the treatment chamber and also by preventing the lime from coming into contact with the moist air in the treatment chamber previous to the projection of the lime into the liquid.

Other features of the invention and details of operation will be set forth in the following specification and claims and illustrated in the accompanying drawings in which—

Figure 1 represents a view of the outside of a machine embodying the features of the invention.

Fig. 2 represents a side view of the structure shown in Fig. 1 and illustrates in section the construction of the lime distributing device within the treatment chamber.

Referring in detail to the drawings 1 indicates the cylindrical wall of the main treatment chamber inclosing the lime distributing device in the upper portion and the cooling apparatus in the lower portion. The cooler pipes or tubes are indicated by 2 and the space surrounding these pipes for the body of the cooling solution is indicated by 3. In the lower half of the chamber 1 and arranged around the inside of the chamber are the cooling pipes 2 providing a central well 4 which is substantially cylindrical in shape. A cover plate 5 extends across the top of the well 4 and is provided with openings therethrough 5^a. The inlet and outlet for the sugar solution are indicated by 5^b and 5^c respectively. The solution is supplied to the casing until the level is reached as indicated by X opposite the sight glass 1^b, and circulation of the solution is effected by the propeller wheel 6 located at the bottom of the well 4. The operation of the wheel 6 forces the material at the bottom of the casing 1 upwardly through the cooling pipes 2 into the lower part of the upper casing. Here the solution flows centrally

over the cover plate 5 and is drawn downwardly by gravity and the action of the propeller wheel 6. Extending downwardly from the upper end of the casing 1 and situated substantially centrally thereof is the metal casing or housing 7 for conveying the particles of lime which are to be distributed. The lowermost end of the casing 7 is somewhat enlarged and extends slightly beneath the upper surface of the material of the sugar solution. Located immediately above the surface of the solution and in the lower end of the casing 7 is the distributing and propelling fan member 8 the function of which is to evenly divide the dry lime particles and to project the same downwardly and into the sugar solution immediately below the member 8 and within the confines of the end of the casing 7. Suitable actuating power is supplied by means of a shaft 9 which is supported at its lowermost end by bearing 9^a secured to the casing 1 by means of the brace 9^b. The lime is conveyed to the casing 7 from a distributing scroll 10 to which the lime is conveyed by connection 11 having a flexible joint 10^a with the scroll 10, from a hopper and weighing scales 12. Located in the upper half of the chamber 1 is a suitable sight glass 1^b and a larger inspection door 1^a which may be opened if it is necessary to reach the inside of the chamber. 9^c denotes a grease cup for supplying lubricant to the bearing 9^a.

The operation of the apparatus will be understood from the foregoing description of the parts and the following explanation: As stated the sugar solution flows upwardly through the cooler tubes and downwardly through the well 4, the upper level of the solution being normally at the point X which is slightly above the lowermost end of the casing 7. When the distributor 8 and the propeller wheel 6 are moved the finely divided dry particles of lime are projected onto the surface of the sugar solution within the casing 7. During this movement the sugar solution has a constant flowing movement toward the center of the casing 7 to a point beneath the casing 7 and from this position downwardly through the openings 5^a. The dry lime particles are effectively prevented from coming into contact with the hot moist air within the chamber 1 and outside of the casing 7 by the action of the sugar solution covering the lowermost end of the casing 7 and substantially providing an air seal at that point. The member 8 is constructed in such a manner that when it rotates, it throws the lime downwardly and at the same time spreads it uniformly over the solution directly under the housing or casing 7. The invention prevents the lime particles from being thrown against or otherwise coming into contact with the inner walls of the chamber 1 before being thor-

oughly co-mingled with the sugar solution. The lime has no opportunity to slake before being projected into the solution because of the operation of the air seal at the bottom of the casing.

From the foregoing it will be clear that the amount of lime necessary for the treating of a given portion of sugar solution is reduced to a minimum because of the efficient distribution of the lime over the surface of the solution treated. This efficient operation makes possible the increased capacity of the apparatus as a whole and the resultant treatment of a larger daily amount of solution.

The process and apparatus described herein may be applied to the mixing of any dry particles or substances to any solutions or liquid and is not limited to the combination of powdered lime to sugar solution.

What we claim is:—

1. The process of applying a hygroscopic powder in a dry state to a fluid which comprises the mechanical distribution of a dry powdered material evenly over a substantially smooth horizontal part of the surface of the fluid to be treated without contact by the powdered material with the damp air in contact with the remainder of the surface of the fluid.

2. The process of applying dry powdered lime to sugar solutions which consists in spreading and forcibly projecting the dry powdered lime evenly on a substantially smooth horizontal part of the surface of the fluid to be treated without contact by the dry powdered lime with the damp air in contact with the remainder of the surface of the fluid.

3. The process of applying dry powdered lime to sugar solutions which consists in forcibly projecting and evenly distributing dry lime particles over a specific and substantially smooth horizontal area on the surface of a portion of the solution to be treated and maintaining the said specific area hermetically separate from the surface of the remainder of the solution.

4. An apparatus for applying powdered material in a dry state to a fluid which comprises a main treatment chamber adapted to contain a fluid to be treated, a series of cooling tubes in the lower portion of said chamber providing a central well, a perforate cover plate over the upper end of said well, circulating means for forcing the liquid upwardly through said cooling tubes from which it is adapted to flow over and downwardly through said perforate cover plate, a downwardly projecting distributing casing over said cover plate, and a distributing device within said casing adapted to project particles of material evenly over the fluid over said cover plate.

5. An apparatus for applying hygroscopic

powdered material in a dry state to a fluid which comprises a main chamber adapted to contain a fluid to be treated, a downwardly projecting distributing casing adapted to extend into the fluid within said chamber and within which the fluid tends to rise to the level of that in said chamber, and a distributing device within said casing for evenly distributing the particles of powdered material over the surface of the fluid within said distributing casing.

6. An apparatus for applying hygroscopic powdered material in a dry state to a fluid which comprises a main chamber adapted to contain a fluid to be treated, a downwardly projecting distributing casing adapted to extend into the fluid within said chamber and within which the fluid tends to rise to the level of that in said chamber, and a distributing device within said casing for evenly distributing the particles of powdered material over the surface of the fluid within said distributing casing, comprising a rotary propeller fan member mounted to rotate on a vertical axis immediately above the level of the liquid.

7. An apparatus for applying hygroscopic powdered material in a dry state to a fluid which comprises a main treatment chamber adapted to contain a fluid to be treated, a downwardly projecting distributing casing adapted to extend into the fluid within said chamber whereby the fluid hermetically closes the lower end of said casing and prevents atmospheric communication between the interior of said chamber and the interior of said casing, and a dis-

tributing device within said casing for evenly distributing the dry particles of powdered material over the surface of the fluid within 40 said distributing casing.

8. An apparatus for applying hygroscopic powdered material in a dry state to a fluid which comprises a main chamber adapted to contain a fluid to be treated, a 45 downwardly projecting distributing casing, and a distributing device within said casing adjacent the substantially level surface of the fluid beneath said casing for evenly distributing the dry particles of powdered ma- 50 terial over the level surface of the fluid, the fluid within said chamber having a central flowing movement to a point beneath said distributing casing and downwardly there- 55 from.

9. An apparatus for applying hygroscopic powdered material in a dry state to a fluid which comprises a main chamber adapted to contain a fluid to be treated, a downwardly projecting distributing casing adapted to 60 extend into the fluid within said chamber, and a distributing device within said casing and adjacent the surface of the fluid for evenly projecting dry particles of powdered material into said fluid, comprising a rotary 65 propeller member mounted to rotate on a vertical axis, the fluid within said chamber having a central flowing movement toward a point beneath said distributing casing and downwardly therefrom.

In testimony whereof we affix our signatures.

JAMES WALTER ADAMS.
OTTO HENRY EGGE.
